UNITED STATES PATENT OFFICE.

JACOB ZITZERMAN, OF BROOKLYN, NEW YORK.

FURNITURE-COVERING-PAD CONNECTER.

Application filed April 20, 1927. Serial No. 185,229.

This invention relates to connecting devices and has particular reference to a device for connecting furniture covering pad sections to retain the same in co-related or juxtaposition.

It has been observed that heretofore covering pads especially of the type which are used on tables and which include a plurality of sections, have been provided with no means for connecting and holding the same in co-related or juxtaposition. It therefore follows that the pad sections in some instances are displaced or separated causing overturning of the articles set upon the table, and in some instances a separated pad section may be tilted or canted to such an extent as to upset and spill the contents of dishes or break table-wear.

It is therefore the principal object of the present invention to provide a means for detachably connecting the sections of a sectional furniture covering pad, which, in addition to securely locking the sections in co-related or adjusted position, includes means for readily effecting the release and separation of the sections.

The invention furthermore comprehends in a sectional furniture covering pad, inter-engaging means for locking any combination of two or more pad sections and releasing means therefor.

Other objects reside in the simplicity and compactness of the locking and releasing means, the economy with which a pad including said means may be produced, and the general efficiency and utility derived therefrom.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a plan view of a pad equipped with a locking means constructed in accordance with the invention and illustrating the section of the pad in locked co-related position;

Fig. 2 is a longitudinal sectional view taken

approximately on the line indicated at 2—2 in Fig. 3;

Fig. 3 is a horizontal sectional view taken approximately on the line indicated at 3—3 in Fig. 2;

Fig. 4 is a detail enlarged sectional view of the edge locking means;

Fig. 5 is a detail sectional view of the spring hinge member constituting a feature of the invention.

Referring to the drawings by characters of reference, 10, 11 and 12 designate, respectively, the outer and intermediate sections of a table pad, each section of which in the present instance is provided with an intermediate layer or ply 13 and outer covering plies 14 and 15, which are suitably secured in place and the outer free edges of which are bound by a binding element 16. The intermediate ply 13 is composed of two superimposed plies of relatively different thicknesses, namely, a thick ply 13^a and a thin covering ply 13^b. The thick ply 13^a is rabbeted or recessed at 17 to accommodate the locking and releasing elements of the connecting device. The outer section 11 has mounted in the recessed portion 17, an element 18 for sliding movement, the element 18 being formed with laterally spaced arms 19 having notched or hooked terminals 20 which are normally retracted within the confines of the section 11 by springs or other equivalent retracting means 21. The ply 13^a has arranged in the recessed portion 17, suitable guide elements 22 in which the arms are slidable and the element 18 is further provided with a central guide projection 23 which is slidable in a guide tunnel 24. The element 18 is provided with a stem 25 having a head 26 which, when the terminals 20 are normally retracted within the confines of the section 11, is disposed adjacent the opposite edge in a convenient position for manipulation.

The end or outer section 10 is formed with laterally spaced keeper tunnels 27 corresponding in spacing to the lateral spacing of the arms 19 and terminals 20, and said keeper tunnels have associated therewith and laterally projectable therethrough, retaining bolts 28 normally urged to a retaining position by a spring 29 to interengage with the hooked or notched terminals 20 to lock the sections in co-related or adjusted positions. The intermediate section is similarly provided adjacent one side edge, with the laterally spaced

keeper tunnels 27 and retaining bolts 28. The end or outer section 10 is provided with a releasing member 30 having laterally spaced longitudinally extending arms 31 provided with cam terminals 32, which are designed to co-operate with cam pins 33 on the retaining bolts 28. Springs 34 normally retract the element 30 and its arms 31 to permit the springs 29 to function to dispose the retaining bolts in their active position. The releasing element 30 is further provided with a stem 35 having a manipulating head 36 which is normally disposed adjacent the opposite edge of the pad section in a convenient position for manipulation. Upon inward pressure exerted on the head 36, the releasing element 30 and its arms 31 will be moved to cause the cam faces 32 to retract the retaining bolts 28. The intermediate section 12 is also provided with a releasing element of precisely the same construction as the releasing element in the section 10.

In use, when the sections are to be correlated and locked in juxtaposition, the locking elements 18 are manipulated by means of the heads 26 to project the hooked or notched terminals 20 beyond the confines or edges of the sections, and at the same time said terminals are inserted in the keeper tunnels 27 of an adjacent section to cause the spring-pressed retaining bolts 28 to engage the same and lock the sections together. When it is desired to separate the sections the releasing elements 30 are manipulated as heretofore described.

Usually the pad sections include foldable portions and in the present instance the locking and releasing elements are disposed within the intermediate foldable portion of each section. In order to hold the edges of the outer portion in alinement, in some instances it may be found desirable to employ means for this purpose, in which case a member including hingedly connected leaves 37 is employed. Each leaf 37 has adjacent its free end a hooked or notched terminal member 38 corresponding to the terminals 20 of the arms 19 and the outer portion of the outer section of the pad is provided with a keeper tunnel 39 having a spring-pressed retaining bolt 40 corresponding to the retaining bolts 28, which bolt 40 is normally moved to an active position by a spring 41. The bolts 40 are provided with cam pins 42 and the extremity of the leaf 37 is provided with a spring retracted button 43 having a cam terminal 44 operable upon inward movement by pressure upon the button, to engage the cam pin 42 to retract

and release the retaining bolt 40 from the notched or hooked terminal member 38.

As a further feature, the foldable pad section portions may be provided with a spring hinge 45 which operates to normally swing the portions into alinement.

What is claimed is:

1. A sectional furniture covering pad including internally disposed means for rigidly locking the sections in juxtaposition comprising normally retracted manually projectable hooked elements within the confines of one section and keeper elements within the confines of an adjacent section, said keeper elements including manually operable means for releasing the same.

2. A sectional furniture covering pad including internally disposed means for rigidly locking adjacent pad sections in juxtaposition, said means consisting of normally retracted manually projectable hooked elements within the confines of one section and keeper elements within the confines of an adjacent section including spring pressed bolts engageable with the hooked elements and means for releasing the bolts of the keeper elements.

3. The combination with a sectional furniture covering pad, of internally disposed means for rigidly locking adjacent sections thereof in juxtaposition comprising normally retracted manually projectable hooked elements disposed when retracted within the confines of one section and keeper elements disposed within the confines of an adjacent section, the said keeper elements including spring pressed bolts adapted to engage with the manually projected hooked elements and means for releasing the locking means for the pad sections including manually operable keeper bolt retracting devices.

4. A furniture pad including a plurality of sections, means within the confines of one section adapted to be manually projected into an adjacent section and means in said adjacent section adapted to receive and lock the first means to rigidly hold the said sections in abutting juxtaposition.

5. A furniture pad including a plurality of sections, means within the confines of one section adapted to be manually projected into an adjacent section, means in said adjacent section adapted to receive and lock the first means to rigidly hold the said sections in abutting juxtaposition and means in the receiving section for releasing the first means whereby to disconnect the pad sections.

JACOB ZITZERMAN.
